WINDOW CONSTRUCTION

Mason P. Rumney and Clyde W. Kelly, Detroit,
Mich., assignors to Detroit Steel Products Com-
pany, Detroit, Mich., a corporation of Michigan

Application August 17, 1931, Serial No. 557,660

4 Claims. (Cl. 189—69)

The invention relates to window constructions and refers more particularly to window constructions of that type having skeleton frames and sashes mounted on said frames and movable to open and closed positions. One of the objects of the invention is to provide an improved window construction comprising a skeleton frame, a sash and a sub-frame, which together are adapted to form a fabricated self-contained unit insertable 10 into a wall opening and in which the sub-frame forms both the inside and the outside trim. Another object is to so form the window construction that the sub-frame forms a guide for and overlaps the plaster. Further objects are to provide an 15 inside screen and either or both an operator and a fastener for the sash operable from inside the skeleton frame without disturbing or opening the screen; and to mount either or both the operator and the fastener upon the sub-frame. These and 20 other objects of the invention will become apparent from the following description, taken in connection with the accompanying drawings, in which

Figure 1 is an inside elevation of a window construction, showing an embodiment of my invention and in a wall opening;

Figures 2 and 3 are enlarged cross sections, respectively, on the lines 2—2 and 3—3 of Figure 1;

Figure 4 is an inside elevation of Figure 2;

Figure 5 is a plan view of the operator shown in Figure 3;

Figures 6, 7, 8 and 9 are views similar to Figure 2; showing other embodiments of my invention.

As shown in Figures 1 to 4, inclusive, the window construction comprises the skeleton frame 1, the sash 2 on the frame and the sub-frame 3, the frame, sash and sub-frame together being adapted to form a standardized fabricated self-contained unit insertable into an opening in the wall 4. To provide for inserting this unit, either the inside portion or the outside portion of the wall may be first built up and the unit then inserted into the opening, after which the other portion of the wall is assembled.

The skeleton frame 1 is a metal frame, the bars of which are substantially Z-shaped in section. The sash 2 also has metal bars of Z-shaped section and this sash is movable to open and closed positions and, in the present instance, the sash is an outwardly swinging sash. Both the frame and the sash, as shown in the present instance, are of standard construction. The sub-frame 3 is shown as formed of wood. This sub-frame surrounds the frame 1 and has a portion fitting the bars of this frame and fixedly secured thereto as by means of the wood screws 5. The jamb members of the sub-frame each comprises the section 6 which extends laterally outwardly from the frame 1 and which is anchored in the wall opening and the section 7 which extends transversely

of the section 6 and toward the inside of the building or room. The section 6 has the outside face 8 intermediate the skeleton frame 1 and the wall provided with a suitable contour and finish to form the outside trim. The section 7 has the lateral inner face 9 which is provided with a suitable contour and finish to form the inside trim. Furthermore, this section 7 forms a guide for the plaster 10, this section having the projection 11 extending transversely inward or toward the inside of the building or room for overlapping the plaster 10 and forming the guide therefor.

The window construction is provided with the flat screen 12, the frame 13 of which is adapted to be detachably secured to the inside face of the skeleton frame 1 and to extend closely adjacent to the sash 2 when the latter is in closed position.

For opening and closing the sash, I have provided the operator 14 which is located both laterally and transversely within the wall opening. This operator is of suitable construction, as shown in Figures 3 and 5 particularly, and has the support 15, the operating member mounted upon this support and having the handle 16 and the lever 17 extending within the support and connected to the operating member and provided with the shoe 18 slidably engaging the guide 19, which latter is secured to the lower face of the web of the bottom bar of the sash 2. The support 15 is mounted upon the bottom bar 20 of the sub-frame 3 and fixedly secured thereto by suitable means, such as the wood screws 21. This bottom bar forms the sill member of the sub-frame and its faces inside and outside the skeleton frame 1 are suitably finished. The operator is located between the bottom bar of the frame 13 of the inside screen and the bottom bar of the sill member 20 and, as shown, the upper face of the support 15 is recessed at 22 to receive the lower edge portion of the bottom bar of the frame 13.

For fastening the sash in closed position I have, as shown particularly in Figures 2 and 4, provided the fastener 23 which comprises the support 24, the fastening member 25, the shaft 26 journalled in the support and having the fastening member fixedly secured to one end thereof and the operating member or handle 27 fixedly secured to the other end thereof. The support is mounted upon the jamb member of the sub-frame adjacent to the free or swinging edge of the sash 2 and, more particularly, the support is secured to the lateral inner face of the section 7 by suitable means such as the wood screws 28. This support is located between the upright bar of the frame 13 of the screen and the section 7 and has the laterally inwardly extending projection 29 for engaging over the inside face of this upright screen bar to assist in

holding the screen in place. The handle 27 is located inside the screen and laterally and transversely within the opening, the shaft 26 extends transversely of the section 7 and the fastening member 25 is in the nature of an arm movable angularly in a path parallel to the skeleton frame. This fastening member is engageable with the keeper 30 which is secured to and extends transversely inwardly from the bar at the free or swinging edge of the sash and the upright screen bar 13 is recessed at 31 to receive both the fastening member and the keeper.

It will thus be seen that both the operator 14 and the fastener 23 are mounted upon and carried by the sub-frame and independently of the skeleton frame and also that both may be operated without disturbing or opening the screen. It will be further seen that the operator and the fastener are adapted to form with the sub-frame the skeleton frame and the sash a standardized fabricated self-contained unit insertable in a wall.

In the modification shown in Figure 6, the arrangement of the parts is similar to that shown in Figures 1 to 5, inclusive, with the exception that the wood sub-frame has its jamb members 32 formed in one piece and constructed so that the sub-frame, the skeleton frame and the sash may more readily be inserted into the wall opening as a standardized fabricated self-contained unit. Another exception is that the fastener 33 is adapted to swing through a path parallel to the lateral inner face of the jamb member and transverse to the skeleton frame and also the sash when in closed position. The fastener has the handle 34, the fastening member or arm 35 and the central portion 36 integral with the handle and the fastening member. This central portion is pivoted upon the plate 37, which is secured to the lateral inner face of the jamb member adjacent to the free or swinging edge of the sash. The fastening member 35 is adapted to swing between this jamb member and the adjacent bar of the screen and is engageable with the keeper 38 which is secured to the upright bar 39 at the free or swinging edge of the sash. This keeper is located in the space between this bar 39 and the adjacent bar 40 of the skeleton frame when the sash is in closed position and the fastening member is adapted to extend through the inside flange of the bar 40.

Figure 7 discloses another modification in which the parts have the same general arrangement as those of Figures 1 to 5, inclusive. However, in this modification the sub-frame 41 is formed of sheet metal, the bars of which are hollow and given suitable contours to form the inside and outside trim, to overlap the skeleton frame 42 and to form an anchor for securing the sub-frame in place in the wall opening. More specifically and as shown, the hollow sheet metal jamb members 43 have the laterally inner offset face portions 44, the transverse flanges 45 and 46 at the edges of these face portions and the portions 47 and 48 respectively connecting into these flanges and extending parallel to but spaced from the faces 44. The flanges 45 overlap the outside flanges of the bars of the skeleton frame and the flanges 48 overlap and guide the plaster 49. These jamb members are also provided with the transverse flanges 50 which are adapted to extend between the inside and outside portions of the wall. In this modification, the fastener 51 is constructed and ar-

ranged in the same manner as the fastener 33, shown in Figure 6.

In the modification shown in Figure 8, the arrangement is in general the same as that shown in Figures 1 to 5, inclusive, with the exception that the fastener 52 is mounted upon the inside or room side face 53 of the jamb member 54, which is adjacent to the free or swinging edge of the sash. In this case the handle 55 and the fastening member 56 swing through a path parallel to the skeleton frame and also the sash when in closed position and the central portion of the fastener is located between the screen 57 and the section 58 of the jamb member. This section may be made a part of the sub-frame and inserted into the wall therewith, or, if desired, it may be secured to the sub-frame after the plastering. In either event, the sub-frame has the section 59 secured thereto and forming a part thereof which is adapted to guide the plaster and by means of which the section 58 is secured to the sub-frame.

Figure 9 discloses another modification in which the sub-frame is formed of sheet metal and its bars are preferably hollow and are shaped to form the inside and outside trim and to anchor the sub-frame and, consequently, the skeleton frame in the wall. In this modification, it is to be noted that the jamb members 60 have the inside or room side faces 61 and, extending from these faces and toward the interior of the building or the room the flanges 62 having the return-bent, terminal portions 63 which overlap and guide the plaster 64 and form anchors. The jamb member adjacent the free or swinging edge of the sash has its face 61 sufficiently wide to mount the fastener 65 thereon, this fastener being constructed in the same manner as the fastener 52, shown in Figure 8.

What we claim as our invention is:

1. A widow construction, comprising a skeleton frame, a movable sash on said frame and a sub-frame, said frame, sash and sub-frame being adapted to form a fabricated self-contained unit insertable into a wall opening, and an operator for said sash mounted on said sub-frame.

2. A window construction, comprising a skeleton frame, a sash on said frame movable to open and closed position and a sub-frame, said frame, sash and sub-frame being adapted to form a fabricated self-contained unit insertable into a wall opening, and a fastener for holding said sash in closed position, said fastener being movably mounted on the lateral inner face of said sub-frame and having a portion extending transversely of said sash in closed position for fastening the same.

3. A window construction comprising a skeleton frame, a sash on said frame movable to open and closed positions and a sub-frame, said frame, sash and sub-frame being adapted to form a fabricated self-contained unit insertable into a wall opening, and a fastener for holding said sash in closed position, said fastener being mounted on the inside face of said sub-frame and having a portion movable substantially parallel to said sash when closed for fastening the same.

4. A window construction, comprising a skeleton frame, a movable sash on said frame, a sub-frame, and an operator for said sash having a support mounted on said sub-frame, said frame, sash, sub-frame and support being adapted to form a fabricated self-contained unit insertable into a wall opening.
